COMBINED PULL AND BACKING PLATE

La Verne E. Clayton, Rockford, Ill., assignor to
Amerock Corporation, Rockford, Ill., a corpora-
tion of Connecticut

Filed June 6, 1968, Ser. No. 12,240

Term of patent 14 years

U.S. Cl. D8—138
Int. Cl. D8—03

FIGURE 1 is a front view of a combined pull and backing plate incorporating my new design.

FIG. 2 is a side view of the combined pull and backing plate as seen from the right of FIG. 1.

FIG. 3 is a top view.

FIG. 4 is a perspective view of the combined pull and backing plate.

FIG. 5 is an enlarged sectional view taken along the line 5—5 in FIG. 2.

FIG. 6 is an enlarged sectional view taken along the line 6—6 in FIG. 1.

I claim:

The ornamental design for a combined pull and backing plate, as shown.
